GUITAR OR SIMILAR ARTICLE

Joseph L. Baker, Nashville, Tenn., assignor to Baker-Lewis Music Enterprises, Inc.

Filed Aug. 12, 1966, Ser. No. 3,443

Term of patent 14 years

(Cl. D56—1)

The conventional neck and strings have been substantially omitted for convenience of illustration.

Portions of the drawing figures are lined to indicate color contrast.

I claim:

The ornamental design for a guitar or similar article, substantially as shown and described.
